Des. 206,900
Patented Feb. 7, 1967

206,900

HAIR TINTER DISPENSER

Lowell R. Hagedorn, 3041 Lakeshore Blvd.,
Wayzata, Minn. 55091

Filed June 16, 1965, Ser. No. 85,757

Term of patent 7 years

(Cl. D52—2)

FIG. 6

FIG. 1

FIG. 4

FIG. 3

FIG. 2

FIG. 5

FIG. 1 is a perspective view of a hair tinter dispenser embodying my new design.

FIG. 2 is a front elevational view of the same.

FIG. 3 is a side elevational view of the same.

FIG. 4 is a top plan view of the same.

FIG. 5 is a bottom plan view of the same.

FIG. 6 is a rear elevational view of the same.

The side opposite FIG. 3 is substantially a mirror image thereof.

I claim:

The ornamental design for a hair tinter dispenser, as shown and described.
